UNITED STATES PATENT OFFICE.

EDWARD B. SMITH, OF RICHLAND, MICHIGAN, ASSIGNOR OF ONE-HALF TO
PATRICK H. GILKEY, OF SAME PLACE.

LAMP-LIGHTER.

SPECIFICATION forming part of Letters Patent No. 269,241, dated December 19, 1882.

Application filed October 27, 1882. (No model.)

To all whom it may concern:

Be it known that I, EDWARD B. SMITH, a citizen of the United States, residing at Richland, county of Kalamazoo, State of Michigan, have invented a new and useful Lamp-Lighter, of which the following is a specification.

My invention has for its object the construction of a device for lighting a lamp, consisting of a percussion-wick, means for raising it, a friction-shot bolt or hammer for causing said wick to ignite, and a gate for extinguishing the percussion-wick by fixing a limit to its consumption.

In the drawings forming a part of this specification, Figure 1 is a plan view of a part of the construction, looking from the body of the lamp upward against the under face of the burner; Fig. 2, top view; Fig. 3, vertical section on dotted lines in Figs. 1 and 2; Figs. 4 and 6, detached parts hereinafter described, and Fig. 5 the percussion-wick.

R is the main wick-tube, with wick L. T is the burner. A vertical tube, B, is located at one side of tube R, and is provided with the percussion-wick F. This wick may be made of fabric coated with any substance which will ignite by friction. Said wick F is raised by toothed wheels n of the revoluble shaft a, Figs. 1, 3, 4. The friction-shot P for causing the percussion-wick to ignite is thrown out or shot by spring r r. It is provided with arms a a', which have downwardly-extending lugs S S at each end, Figs. 1 and 3. The shaft a is provided with arms or loops c c, which, when said shaft is revolved, engage lugs S S, for the purpose explained in the operation.

v is a spring-actuated gate, pivoted in a position to shut against the percussion-wick F, preventing said wick from burning below this point, Figs. 1, 3, 6. Gate v is provided at one end with a downward extension, v', which is acted upon by one of the arms c at the proper time to shut said gate against the wick.

In the operation the shaft a is revolved,

which turns up the percussion-wick F, and by 45 the engagement of arms c c with lugs S S the friction-shot P is thrown back away from the wick. As soon as arms c c release the lugs S S the friction-shot is thrown forward by the elastic force of springs r r, the pointed end engaging the wick and lighting it. One of the arms c then engages the extension v' of gate v, shutting said gate against the wick, as before stated.

The device having plates D and A, here 55 shown, is especially intended for a lantern; but my lighter may be applied to any style lamp desired.

Having thus described my invention, what I claim is—

1. A lamp-burner having a percussion-wick tube located at the side of the tube containing the wick to be lighted, in combination with a friction-shot, a gate for limiting the consumption of the percussion-wick, and means for 65 raising said wick and for operating the friction shot and gate, substantially as set forth.

2. The percussion-wick and the revoluble shaft for raising it, provided with the arms for operating the friction-shot, in combination 70 with said shot provided with the lugs for engagement with said arms, substantially as specified and shown.

3. In a lamp-lighting device, the combination, with a percussion-wick and means for 75 raising it, provided with the arms, of a friction-shot provided with the arms and lugs, and a gate having a projection for engaging one of said shaft-arms, substantially as described and shown.

4. The shaft having the loop-arms and the gate provided with the extension for engaging one of said arms, in combination with the wick.

EDWARD B. SMITH.
